CLAIM

The ornamental design for a container for tire sealant with attached device for injecting tire sealant into vehicle tires, as shown and described.

DESCRIPTION

FIG. 1 is a perspective view of the container for tire sealant with attached device for injecting tire sealant into vehicle tires of the present invention;

FIG. 2 is a left side view of the container for tire sealant with attached device for injecting tire sealant into vehicle tires of FIG. 1;

FIG. 3 is a right side view of the container for tire sealant with attached device for injecting tire sealant into vehicle tires of FIG. 1;

FIG. 4 is a front view of the container for tire sealant with attached device for injecting tire sealant into vehicle tires of FIG. 1;

FIG. 5 is a rear view of the container for tire sealant with attached device for injecting tire sealant into vehicle tires of FIG. 1;

FIG. 6 is a top view of the container for tire sealant with attached device for injecting tire sealant into vehicle tires of FIG. 1; and,

FIG. 7 is a bottom view of the container for tire sealant with attached device for injecting tire sealant into vehicle tires of FIG. 1.

The broken lines in the drawings depict unclaimed environmental subject matter.
